E. BYNE

TENT

Filed Jan. 19, 1927

UNITED STATES PATENT OFFICE.

EDWARD BYNE, OF GABYON STATION, WURARGA, WESTERN AUSTRALIA, AUSTRALIA.

TENT.

Application filed January 19, 1927, Serial No. 162,182, and in Australia February 4, 1926.

This invention relates to tents or shelters which have jointed frames which are easily collapsible. One object of the invention is to provide a tent frame composed of ribs which are relatively light and are connected together, and are tensionable into arcuate form. These ribs will carry a fabric body.

My tent has means by which it can be firmly and easily anchored. It can be rapidly erected and is portable.

A further feature of the invention is that the frame when erected has a base of the form of a segment of a circle, and has, rising from the base, arched ribs which extend in different directions and are held in tension, one or more transverse droppers being added to stay the arches when required. In side view the tent frame has a vertical or an oblique front.

The tent can be rapidly collapsed because the joints of the frame allow of folding. When the tent is erected its contour promotes deflection of wind striking its exterior, and the said contour also provides a maximum of interior space. Such shelters are suitable for temporary use on beaches, and by travellers.

The fabric of the shelter may vary. It is waterproof and lightproof if desired, and may be silk, canvas, or other light strong flexible material. This fabric can be reinforced in the vicinity of frame hinges by means of patches—the same description of fabric not being necessarily used at all parts of the tent.

The foregoing and other details are explained herein by reference to the drawings herewith in which scales vary.

Figure 1 shows, in perspective, my tent erected, part of the fabric being omitted.

Figure 2 shows, in front elevation, the frame erected.

Figure 3 is a side elevation of the tent with part of the fabric omitted.

Figure 4 is a perspective view of parts where bases of ribs are connected.

Figure 5 is an elevation, partly in section, of a rib joint and adjacent fabric.

Figure 6 is an elevation of a fully opened rib joint, with the rib curved under tension.

Figure 7 is a fragmentary view of a dropper.

Figure 8 shows a partly folded rib.

Figure 9 is a perspective view of a hinge fitting.

Figure 10 is another view of the part in Figure 9.

Figure 11 is an elevation, omitting the fabric, of a variation of Figure 5.

Figure 12 shows partly in vertical middle section, part of a tensioned rib having a joint of modified construction.

The frame includes a base rib 1, and a front arch 2, and has intermediate ribs 3, and one or more droppers 4, the latter being omittable at will, their use being chiefly desirable in relatively large shelters. Each rib has any suitable number of joints 3^a, 4^a respectively; and each dropper is jointed when, owing to its length, that construction enables the dropper to be folded to advantage.

Across the front of the shelter is a tensioning means shown as a cable 10 which extends along or a little above the ground, and by which the series of arcuate members of the frame have their meeting ends held together in two groups one at each side of the shelter, and so spaced apart as to maintain suitable rib tension, whereby the fabric of the shelter will be given the correct shape for use, for example that of a quarter or more than a quarter of a hollow sphere.

The joints at groups of rib ends may vary, Figure 4 exhibiting a screwthreaded stem 5, which passes through each rib end, a wing nut 5^a fixing the end with the ribs extending in their appropriate planes. The tensioning cable 10 is shown with end adjustment links 10^a one of which engages stem 5, the end of which, 5^b, is hooked.

16 shows the shelter fabric which covers the frame, and 16^a are rib attachment means, shown as slots for example. The fabric front has edge frilling by which two shelters, set front to front, are connectible to form a dome shaped tent of large internal capacity, but any other front parts of two shelters may be connected to make a larger tent. I provide one or more front curtains at will to hang vertically or to extend obliquely. A front frill 8 may support any such curtain; but, though useful, curtains are not illustrated as they are not claimed. I use a front frill for anchor cable connections, cables or cords 8^a being shown tensioned by suitable means, as ballast bags 9, for example.

The front frill extends around any predetermined length of the front arch, and is of

suitable width, for example less than 12 inches, in a shelter of small size made for one or a few occupants. The front frill can slope outward forward of the vertical plane of the ground line cable 10. The user can, however, at will set the frill back inside the shelter, or minimize the space it occupies. For this purpose press buttons are suitable.

The fabric base has a frill 11, extending around any predetermined length of the base rib 1, constituting a ground contact which will keep out water and wind and to act as an anchor when loaded, sand 11^a being very suitable, and, on beaches, the best anchoring means; but when such use is not desired the frill 11 can be located inside the shelter, for which purpose press buttons are suitable.

To ensure that the contour of the fabric shall be externally convex, the material of the fabric is cut into strips of suitable pattern which are united by sewing, for example.

I find it advantageous to employ lengths of spring steel to form the ribs, the lengths having joints which allow of opening the ribs out straight, but resist further openings so that the ribs when pressed further in the opening direction become curved into arches under tension, the curves being such as are maintained by the frontal connection 10. In Figures 5, 6, and 11 the ribs are of the familiar channelled cross section, but the sections may vary, and the flexible material is not necessarily metal. Any length of channelled rib may have at its ends some other suitable section.

In Figure 12 rib length ends 3^b, 3^c do not meet, but approach one another and have a flexible connection 3^d, of leather for example, to form the foldable joint. The ends of this connection are suitably fixed as by being squeezed in rib channels. A sleeve 3^e is adjustable to prevent the joint closing when in the position shown, but by sliding the sleeve off one rib length, the rib joint becomes foldable. When the sleeve holds the rib extended the rib is tensionable to produce an arch. To hold the sleeve in position, means, shown by springs 3^f, 3^g, are used. One of these springs, 3^f, locks into a sleeve slot 3^h, but when the sleeve is adjusted for rib folding, spring 3^f enters slot 3^h.

The hinge in Figure 11 has a central abutment block 14 the ends of which carry two hinge pins 14^a connecting the limbs 12^b, 12^c; and a projection 14^b of this block forms abutments for the limbs and ensures easy tensioning of the rib. Obviously a block part, 14^b, could be arranged with projections to enter rib limb sockets by making slight modifications. I show a socket in Figure 5 which shows a modified joint, and in which

the hinge 12 has a pin 12^a passing through

its limbs 12^b, 12^c; limb 12^b has a tongue 13 projecting into a socket 13^a in limb 12^c, this combination affording resistance to lateral distortion of the joint.

Figures 9 and 10 show a hinge limb 12^d 70 which is adapted to be fixed to a length of rib as a jointing member.

Unless subjected to a powerful head wind my shelter when erected will stand without requiring to have its front anchored by stays, especially when fitted with one or more of the droppers which I next describe. By way of example I show a dropper 4 of flat spring metal, with intermediate and end locking devices shown as recesses 15, 15^a to 80 engage and hold in place respective ribs 3, 2, and 1 of the shelter, and counteract any tendency such ribs may have to fall from their correct positions. The dropper is curved under tension when in use; and, in the case illustrated, stands in a vertical plane. It has a joint 4^a when that is preferred.

I employ anchoring cords 8^a in pairs, spreading two pairs suitably to hold or assist in holding the frame erected, notwithstanding that there may be wind at the front; but cord details are variable, and any number of cords or straps can be used.

Other variable and optional details are 95 laces, hooks, pockets, eyelet holes, ventilators, and other obvious conveniences, which can be readily understood, and which I do not illustrate or claim.

My shelter can be so made that it will 100 when in use be folded up and re-erected without removing the fabric from the frame; or the fabric is made separable, and for relatively large shelters it is most suitable to employ separable fabric.

I claim:—

1. In a shelter frame, a foldable and flexible rib adapted to be flexed into a curve and to be folded into shorter lengths by opposite movements in the same plane and means on each end of the rib for attachment of a tensioning member to hold the rib in its curved position.

2. In a shelter frame comprising a series of longitudinal, pivotally jointed flexible members adapted to be forced in one direction to form a series of spaced apart spring ribs and to be folded in the opposite direction, supporting members for the ends of the ribs and tensioning means connecting the 110 rib supporting members.

3. In a shelter frame comprising a series of longitudinal, pivotally jointed flexible members adapted to be forced in one direction to form a series of spaced apart spring ribs and to be folded in the opposite direction, supporting members for the ends of the ribs and detachable tensioning means connecting the rib supporting members.

4. In a shelter frame comprising a series 130

of longitudinal, pivotally jointed flexible members adapted to be forced in one direction to form a series of spaced apart spring ribs and to be folded in the opposite direction, means for holding the ribs in spaced relation, supporting members for the ends of the ribs and tensioning means connecting the rib supporting members.

5. In a shelter frame comprising a series of longitudinal, pivotally jointed flexible members adapted to be forced in one direction to form a series of spaced apart spring ribs and to be folded in the opposite direction, means for holding the ribs in spaced relation, said means consisting of dropper members secured to adjacent ribs, supporting members for the ends of the ribs and

tensioning means connecting the rib supporting members.

6. A shelter comprising a frame consisting of a series of longitudinal, pivotally jointed flexible members adapted to be forced in one direction to form a series of spaced apart spring ribs and to be folded in the opposite direction, supporting members for the ends of said ribs, tensioning means connecting the rib supporting members, a fabric covering for said frame and frills secured to the marginal edges of said shelter forming means to support and attach holding means for said shelter.

In witness whereof I have hereunto set my hand.

EDWARD BYNE.
